UNITED STATES PATENT OFFICE.

FREDERICK WILLIAM HILL, OF FOLKESTONE, ENGLAND.

DESIGN FOR A SPARKING-PLUG ELECTRODE

57,127.

Specification for Design.

Patented Feb. 22, 1921.

Application filed November 12, 1919. Serial No. 337,616. Term of patent 7 years.

To all whom it may concern:

Be it known that I, FREDERICK WILLIAM HILL, a subject of the King of Great Britain, residing at Folkestone, England, have invented a new, original, and ornamental Design for a Sparking-Plug Electrode, of which the following is a specification, reference being had to the accompanying drawing, forming part thereof.

Figure 1 is an elevation, and Fig. 2 is a lower plan or end view of a sparking plug electrode, showing my new design.

What I claim as new and desire to secure by Letters Patent is:—

The ornamental design for a sparking plug electrode, as shown.

In testimony whereof I have hereunto set my hand in presence of two subscribing witnesses.

FREDERICK WILLIAM HILL.
